UNITED STATES PATENT OFFICE.

MOSES MOODY DOWNER, OF BRIDGEPORT, CONNECTICUT.

WIRE CORSET-STAY.

1,075,339.

Specification of Letters Patent. Patented Oct. 14, 1913.

Application filed February 22, 1913. Serial No. 750,162.

To all whom it may concern:

Be it known that I, Moses Moody Downer, a citizen of the United States, residing at Bridgeport, county of Fairfield, State of Connecticut, have invented an Improvement in Wire Corset-Stays, of which the following is a specification.

This invention has for its object to produce a corset stay formed from wire which will remain flat under all conditions, will be alike on both edges, will possess the desired degree of rigidity against forward and backward or sidewise flexion, which will not buckle when flexed sidewise and which will possess the maximum of strength and durability with a minimum weight and consumption of wire.

With these and other objects in view I have devised a corset stay comprising a central looped strand of wire and oppositely wound coiled strands on opposite edges, alternate coils passing through the ends of the loops leaving a coil between each pair of loops.

In the accompanying drawing forming a part of this specification, Figure 1 is an elevation of my novel corset stay on a greatly enlarged scale; and Figs. 2 and 3 are similar views illustrating modifications within the scope of the invention.

For convenience in description I shall refer to the members of the stay as the central strand and the side strands.

10 denotes the central looped strand, which is simply a strand of wire bent alternately toward the right and left to form loops which are specifically indicated by 11.

12 and 13 denote the coiled side strands which are preferably although not necessarily made from the same size of wire as the central strand and are wound in opposite directions.

The method of manufacturing my novel stay is wholly immaterial so far as the present invention is concerned. It is sufficient for the purposes of this specification to state that the coils are threaded into the loops of the central strand, as clearly shown. In the form illustrated in Fig. 1, the loops of the central strand and the coils of the side strands are so spaced apart and so proportioned relatively to each other that alternate coils of each side strand engage a loop of the central strand leaving a free coil between each pair of loops.

The form illustrated in Fig. 2 differs in that the loops of the central strand are closed approximately together at their open ends, giving a slightly pear-shaped form to the loops. This form permits each coil of the side strands, instead of each alternate coil as in the other form, to engage a loop of the central strand, the free coils of the first form being dispensed with, whereby a somewhat more rigid stay is produced.

Where it is required that the stay be still more elastic than in the first form, the desired result may be accomplished by reversing the coils of the side strands, as clearly shown in Fig. 3, that is, making the eyes of the coils, specifically indicated by 14, project inward instead of outward, and engaging the intermediate portions of the side strands, lying between the coils and specifically indicated by 15, with the loops of the central strand and leaving all of the eyes of the side strands disconnected from the loops of the central strand. As shown in Fig. 3, the loops of the central strand are expanded sufficiently to leave an intermediate portion of a side strand and two eyes between each two points of engagement with the central strand. Having engaged the coils of the side strands with the loops of the central strand, the strip, comprising the central strand with the interlocked coils on opposite edges thereof, is passed between rolls, the effect of which is to flatten the strip into shape for cutting into lengths and tipping. It will be noted that in the completed strip the flattened coils of the side strands are slightly twisted, one edge of each coil lying under one side of the loop with which it is engaged and over the other side of said loop.

The interlocking of the loops and coils in the manner described provides an admirable resilient support to every part of the stay. By interlocking alternate coils with the loops and leaving free coils between the loops, as in Figs. 1 and 3, the loops are provided with ample support at all times and it is made impossible for the loops to collapse at one end and expand to any great degree at the other end. The stay, in other words, is given a rigidity that has not existed in any wire stays heretofore produced while at the same time there is ample resilience for both forward and backward and edgewise flexion and without danger of the stay buckling when flexed edgewise.

Having thus described my invention, I claim:—

1. A corset stay comprising a central strand of wire bent into zigzag form with the loops all arranged in the same plane, and side strands each composed of a single wire formed into coils, each loop of the central strand being interlocked with a coil of a side strand, and the coils of said side strands being flattened to substantially the same plane as the loops of the central strand.
2. A corset stay comprising a central strand of wire bent into zigzag form with

the loops all arranged in the same plane, and side strands each composed of a single wire formed into coils, alternate coils of each side strand being interlocked with the successive loops of the central strand on the sides contiguous to said coils.

In testimony whereof I affix my signature in presence of two witnesses.

M. MOODY DOWNER.
